UNITED STATES PATENT OFFICE

2,380,383

BUCKLE

Mary Heloise Ballard, Chicago, Ill.

Application September 14, 1942, Serial No. 458,317

2 Claims. (Cl. 24—163)

This invention relates more directly to a belt buckle and more particularly to the covering thereof. This application is a continuation of my pending application Ser. No. 411,175, filed September 17, 1941.

It is among the objects of this invention to provide a covering for a buckle that can be readily assembled on a buckle frame or removed therefrom and replaced by a different covering in design or color to blend with or match the garments worn.

It is a further object of this invention to provide a covering in the form of a fabric tube which is stretchable or distortable to conform to and closely fit different shapes or different sized cross-sections of the buckle frame.

With these and other objects in view which will become apparent as the description proceeds, this invention comprises the novel structure and method hereinafter described and more particularly pointed out and defined in the appended claims.

In the accompanying drawing which illustrates the preferred form and method of this invention and in which similar reference numerals refer to similar features in the different views:

Fig. 1 is a plan view of a piece of fabric cut on a bias involving a part of this invention.

Fig. 2 is an end elevational view of Fig. 1.

Fig. 3 is a plan view showing the fabric folded upon itself and under longitudinal tension for stitching purposes.

Fig. 4 is an end elevational view of Fig. 3.

Fig. 5 is a plan view of the completed tube reversed and ready for application to a buckle frame.

Fig. 6 is an end elevational view of Fig. 5.

Fig. 7 is an elevational view of a buckle frame with a portion of a covering tube being telescoped thereon.

Fig. 8 is a view similar to Fig. 7 but with the cover telescoped thereon.

Fig. 9 is a plan view of a modified form of buckle with parts broken away.

Fig. 10 is a sectional view taken upon the line 10—10 of Fig. 9 looking in the direction of the arrows.

Fig. 11 is a view similar to Fig. 8 but illustrating a modified form of securing the ends of the covering.

Referring now to the drawing, there is shown in Fig. 1 a suitable strip of fabric 1 which is cut on a bias; that is, it is cut oblique to the warp which extends longitudinally and the weft which

extends transversely. When such a cut piece of fabric is formed into a tube as will later be explained, the warp and weft will become helical.

This strip of fabric is then folded lengthwise upon itself and stretched or put under tension as indicated in Fig. 3 and it is stitched while under tension to form a tube. Stitching the fabric under tension provides what may be termed a loose seam when the tube contracts into the position shown in Fig. 5 and allows the tube to be longitudinally stretched or put under tension when applied to the buckle frame. When sewing the material in a machine, it is possible to put the same under sufficient tension for this purpose.

After the stitching operation, the tube is reversed; that is, it is turned inside out to bring the seam within the interior so that it will be concealed from view. In some forms of the invention, both ends of the tube may remain open and the open ends anchored to the buckle frame. In other forms, one end of the tube may be closed to serve as a stop when the tube is telescoped and stretched over a buckle frame. When it is desired to close one end of the tube, the edge can be turned to provide a double thickness and to improve the appearance as is well known in the art.

The fabric tube 2 should be made of a size or width to substantially correspond to the greatest cross-sectional area of the buckle frame which as a rule varies in cross-section. The buckle frame may have portions considerably smaller than the largest cross-section thereof, nevertheless, the longitudinal stretching or distortion in its application to the frame will cause the tube to nicely conform to such smaller portions as can readily be observed by observing Fig. 9.

In Fig. 7, there is shown a buckle frame 4 having reduced or tapering portions 4a which merge into the terminal portions which are provided with holes 5 thru which the end portions of the tube may be stitched to anchor the same on the frame in taut relation. When such stitching holes are used, both ends of the tube may be left open, especially when it is desired to provide a gap closing or concealing tail on one end of the tube. The buckle frame shown in Fig. 7 is provided with a prong 6 mounted upon one terminal of the frame between the holes 5.

The tube or sheath as it may be termed is adapted to be telescoped over the buckle frame 4 as shown in Figs. 7 and 8 by simply slipping the sheath over the frame. At a suitable distance from the rear end, the tube or sheath may be

stitched to the frame 4 thru the adjacent hole 5. The stitching of the sheath may take place an inch or fraction thereof from the end of the sheath 2 to provide a free end portion or tail 2a which may be used to close and conceal the gap between the terminals of the buckle frame, by extending the same across such gap, telescoping the same upon the opposite terminal of the buckle and securing the same thereto in any approved manner.

With one end of the tube thuswise anchored, the same may be stretched and caused to conform to and closely fit the reduced parts 4a of the buckle frame as shown in Fig. 8. This stretching or tensioning may be done by merely pulling on the free end portion of the sheath. When the sheath becomes properly fitted to the frame by the stretching distortion, the free end may be anchored to the frame by stitching extending thru the adjacent hole 5. Before stitching, the free end of the sheath may be turned in to provide a double thickness and an improved appearance as indicated at 8 in Fig. 8. This stitching is designed to maintain the sheath under proper and close fitting tension.

Fig. 11 shows the same buckle as in Figs. 7 and 8 but illustrates an additional method of securing the ends of the sheath to maintain the same in taut relation on the frame. In this figure the ends 2b of the sheath 2 are drawn outward, flattened and riveted together by an eyelet 9, an operation which may be speedily performed on a machine or by a tool. This method results in also closing or concealing the gap between the terminals of the buckle frame. While Fig. 11 also shows stitching 1 as in Fig. 8, such stitching may be dispensed with if desired when such eyelets are used. The stitching however provides additional strength with respect to the end anchoring means.

In Figs. 9 and 10 there is shown a modified form of buckle which consists of a frame plate 10 having under turned terminal portions 11 one of which is provided with a belt fastening tongue or hook 12. It will be noted that the frame plate 10 has a relatively wide central portion 10a and wide ends 10b with curved depressions or valleys 13 between the central portion and the ends.

The covering tube or sheath 2 for this buckle frame 10 is made of a uniform size or width to slip over the large portions of the buckle frame just as was done in the first form. One end of this sheath 2, the one that fits over the left hand terminal of the buckle frame, is shown closed as indicated at 14. Any approved method may be used for closing such end.

With reference to the drawing, it will be noted that the greatest width or cross-sectional area of the buckle frame is shown as approximately twice the width or cross-sectional area of the most restricted width or cross-sectional area, and that it tapers toward the restricted portion. However, this ratio can be increased to 3 to 1 if desired, or reduced likewise; the tube due to the loose and stretchable seam will closely and smoothly conform to such irregularities. This is an important feature since such irregular buckles are making the greatest progress in the art.

This tube or sheath is adapted to be slipped or telescoped over the left hand terminal of the plate 10 until the closed end 14 thereof engages the end of the plate 10 which may also be provided with stitching holes 5 for additional anchoring means in addition to that provided by

the closed end. In this modification, the anchoring stitching is indicated by the reference 17.

With the left hand end of the sheath anchored as above explained, any pull upon the right hand end portion will stretch or put the sheath under longitudinal tension which will cause the tube to transversely contract and conform to and closely fit the valleys 13 and in fact the entire buckle frame. With the tube under proper tension and distortion as it were, the free end may be anchored and secured to its terminal 11 by stitching 17 or in any suitable manner.

It will be understood that any suitable securing means may be used for anchoring the ends of the sheath; instead of stitching, eyelets may be used for anchoring the ends of the sheath as shown in Fig. 11 or other suitable fastening means may be used.

In Fig. 10, portions of a lady's belt 16 are shown associated with the buckle; one portion being attached to the covering adjacent the terminal of the frame and the other being attached to a keeper 18 that is adapted to fit over the hook 12. However the belt forms no part of this invention except as it may co-operate therewith.

From the foregoing, it should be apparent that this invention produces important new results in covering buckles or in making buckles, especially ladies' buckles. For example, the tubular covering can readily be replaced when worn or it can be replaced by a covering of a different color or design to blend with or match the desired garment. Then the tubular covering can be distorted under tension to conform to and closely fit unequal parts of the buckle frame so that it only is necessary to make the tubular covering to correspond to the largest portion of the buckle; in addition the covering tube may be made of uniform size or width.

I am aware that various changes may be made within the spirit of this invention so I do not propose to limit the patent granted thereon otherwise than necessitated by the prior art and appended claims.

I claim as my invention:

1. A buckle, comprising a frame having terminal portions and an intermediate portion of different lateral dimension tapering into the terminal portions, a fabric tube covering said frame and having helical warp and weft and having a maximum lateral dimension corresponding to the dimension of the wide portion of said frame; said tube having a longitudinally extending loose and stretchable seam, said tube being in taut relation on said frame with the ends secured at said terminal portions, said loose seam allowing said tube to contract when under tension for snugly and smoothly conforming to the restricted portions of said frame.

2. A buckle, comprising a frame having terminal portions and an intermediate portion of a lateral dimension tapering into materially narrower portions, a fabric tube covering said frame and having helical warp and weft and having a maximum lateral dimension corresponding to the dimension of the wide portion of the frame, said tube having a longitudinally extending loose and stretchable seam in taut relation on said frame with the end portions secured for maintaining said taut relation, said loose seam allowing said tube to contract when under tension for snugly and smoothly conforming to the narrower portions of the frame.
